UNITED STATES PATENT OFFICE.

ENGLAND J. BARKER, OF CHICAGO, ILLINOIS.

AUTOGRAPHIC REGISTER.

1,338,167.

Specification of Letters Patent.

Patented Apr. 27, 1920.

Application filed October 11, 1917. Serial No. 195,889.

To all whom it may concern:

Be it known that I, ENGLAND J. BARKER, residing at Chicago, in the county of Cook and State of Illinois, have invented new and useful Improvements in Autographic Registers, of which the following is a full, clear, and exact description.

My invention relates to autographic registers, and particularly to that class of 10 registers in which several rolls of paper are journaled therein and strips therefrom simultaneously extracted from one end after passing over a flat bed or platen.

The object of my invention is to extract 15 the paper by means of unyielding permanently fixed pins, and to advance the strips of paper it is desired to tear off to a position where they can be conveniently grasped by the hand of the operator, and to enable 20 said strips to be torn off in equal lengths each time the same are extracted.

In the drawings:

Figure 1 is a plan view of a portion of an autographic register embodying my improvements.

Fig. 2 is a longitudinal section thereof taken on dotted line 2—2, Fig. 1. Referring to the drawings, A represents fragmentary portions of the side-frames of 30 the register, and B represents a horizontally disposed flat bed or platen, the longitudinal edges of which are flanged downward and supported by transverse rods a that tie the side-frames together. The forward end edges of the side-frames adjacent the top of the register are built forward to provide extensions b, b, substantially as shown in the drawings, and these extensions are provided with bearings for the rock- 35 shaft C, which latter has arms c, c, securely mounted thereon near each bearing. These arms project from shaft C in the same direction and support a transversely disposed segmental plate D on their outer 40 ends. The radius of the periphery described by this plate when rock-shaft C moves on its center is such that its highest point is slightly above the horizontal plane of the platen, and the position of the rock- 45 shaft is such that when at the limit of its rearward movement the rear edge of said segmental plate is below and the forward edge of said segmental plate will be advanced beyond the forward edge of the 50 platen, substantially as shown in the drawings.

Just above and in front of the forward edge of the platen, side-frames A are connected by a cross-bar E and the upper edges of extensions b of said side-frames in advance of this cross-bar are connected by a transverse segmental hood G the curvature of which is, preferably, struck from the center of rock-shaft C and is of such radius as to leave a suitable space between it and 60 segmental plate D. At a suitable point between its ends, plate D is provided with two permanently fixed projecting pins F, F, that are, preferably, placed midway between the center of length and the ends 70 thereof.

The positions of these pins are determined by the position of which is known as "post-holes" in the strips of paper that are withdrawn from the register. These strips 75 of paper have a continuous series of forms of the same length printed on them, and each of these forms has two or more post-holes therein near their forward edge. The strips are passed over the platen, under cross-bar 80 E and between the segmental plate D and the hood, and when withdrawn said strips pass over the tops of pins F until the post-holes register with the same, whereupon the pins pass through said post-holes. The 85 rock-shaft is then moved forward through the medium of a handle g on one end of rock-shaft C, substantially to the position shown in dotted lines in Fig. 2 of the drawings, in which position the forward edges 90 of the strips can be grasped by the fingers of the operator; the center of length of the forward edge of the segmental plate being cut away or recessed, as at h, to facilitate this being done. After the operator has 95 thus grasped the forward edges of the strips of paper he raises them so as to remove the pins from the post-holes and then continues to withdraw said strips a short distance before he releases handle g and permits 100 the segmental plate to return to its original position through the medium of a contraction spring I whose forward end is hooked into a suitable hole near the rear edge of one arm c and whose rear end is hooked 105 or otherwise secured to a peg i projecting from the adjacent side-frame.

In order to prevent the paper from buckling upon the platen when pins F are returned to their rearward position by plate 110 D, as shown in Fig. 2 of the drawings, I have provided a tension-plate K whose up-

per horizontal edge is adapted to bear against the underside of cross-bar E, and whose lower edge is provided with a knuckle that surrounds and is secured to a transverse rock-shaft J which is journaled in the side-frames and is located under the platen back of the segmental plate. This tension-plate K is kept constantly pressing up against the underside of the cross-bar by 10 means of a contraction spring k, one end of which is attached to rock-shaft C and the other end to a pin j projecting down from rock-shaft J.

As shown in the drawings, the forward 15 edge of the platen may be provided with one or more extensions M that curve upward slightly and have a tendency to direct the course of the paper strips when being withdrawn upward over the ends of the pins. 20 These extensions M pass through suitable recesses in the upper edge of the tension-plate and are intended to be very resilient, but said extensions may be dispensed with, if desired.

25 The forward motion of the segmental plate may be limited by means of a stud N projecting from the side-frames, but I prefer to dispense with this stud and to make the extent of this forward movement discretionary with the operator.

In order to assist the operator in determining whether the pins are projecting through the post-holes of the strips, I have provided the hood with peep-holes O, O, at 35 points above where pins F will be when in the positions they occupy at which they first enter said post-holes.

What I claim as new is:—

1. An autographic register comprising an 40 upper and a lower transverse element at the discharge end of the same, said elements being spaced apart and said space constituting a passage through which paper strips having perforations therein may be withdrawn, 45 the lower element being rigid and movable in a fixed arc of a circle and having means also rigid for engaging said perforations when said strips are withdrawn.

2. In an autographic register comprising an upper and lower transverse element at the 50 discharge end of the same, said elements being spaced apart and said space constituting a passage through which paper strips having perforations therein may be withdrawn, and rigid means movable in a fixed 55 arc of a circle for engaging said perforations when said strips are withdrawn.

3. In an autographic register comprising an upper and a lower transverse element at the discharge end of the same, said element 60 being spaced apart and said space constituting a passage through which paper strips having perforations therein may be withdrawn, and rigid means movable in a fixed 65 arc of a circle for engaging said perforations when said strips are withdrawn and means for restoring said means when the same is released.

4. In an autographic register comprising an upper and lower transverse element at 70 the discharge end of the same, said element being spaced apart and said space constituting a passage through which paper strips having perforations therein may be withdrawn, and rigid means movable in a fixed 75 arc of a circle having pins projecting therefrom for engaging said perforations when said strips are withdrawn.

5. In an autographic register comprising an upper and a lower transverse element at 80 the discharge end of the same, said elements being spaced apart and said space constituting a passage through which paper strips having perforations therein may be withdrawn, and rigid means movable in a fixed 85 arc of a circle having rigid pins projecting therefrom for engaging said perforations when said strips are withdrawn, and means for restoring said means when the same is released.

In witness whereof I have hereunto set my hand this 28th day of September, 1917.

ENGLAND J. BARKER.
